UNITED STATES PATENT OFFICE.

CHRISTIAN BODMER, OF NEW BRITAIN, CONNECTICUT, ASSIGNOR TO THE STANLEY RULE & LEVEL COMPANY, OF NEW BRITAIN, CONNECTICUT, A CORPORATION OF CONNECTICUT.

DESIGN FOR A BODY OR FRAME FOR SCRAPERS.

45,983.

Specification for Design.

Patented June 23, 1914.

Application filed November 8, 1913. Serial No. 800,001. Term of patent 14 years.

To all whom it may concern:

Be it known that I, CHRISTIAN BODMER, a citizen of the United States, residing at New Britain, Hartford county, Connecticut, have invented a new, original, and ornamental Design for a Body or Frame for a Scraper, of which the following is a specification, reference being had to the accompanying drawing, forming part thereof and in which—

Figure 1 is a perspective view, and Fig. 2 is a front elevation.

As the drawings show, there is a central main base portion having a flat lower side, and arranged longitudinally on the upper side of this base portion and between the front and rear edges is a wall which inclines rearwardly somewhat. At each end of this main base portion is an outwardly extending and gracefully contoured wing which curves upwardly somewhat. Each wing merges

into the base and the wall by three curved flanges, one flange curving forwardly and merging into the side line or edge of the base forward of the wall, another curving upwardly and merging into the edge of the wall, and the third curving rearwardly and merging into the base at the rear of the wall. The top side of each wing is so contoured as to appear to curve down and merge gracefully into the upper surface of the base and the forward surface of the lower part of the wall.

What I claim is:

The ornamental design for a body or frame for a scraper, as shown and described.

CHRISTIAN BODMER.
